UNITED STATES PATENT OFFICE.

GUY L. FAIRBROTHER, OF MYSTIC, CONNECTICUT.

ROTARY EXPLOSIVE-ENGINE.

No. 891,827.

Specification of Letters Patent. Patented June 30, 1908.
Application filed March 20, 1907. Serial No. 363,872.

To all whom it may concern:

Be it known that I, GUY L. FAIRBROTHER, a citizen of the United States, residing at Mystic, in the county of New London, State 5 of Connecticut, have invented certain new and useful Improvements in Rotary Explosive-Engines, of which the following is a specification.

My invention relates to explosive engines, 10 and more particularly to such engines of a rotary type, wherein a rotor is driven by the explosion of a charge contained and compressed in an adjacent explosion chamber.

The object of my invention is to provide 15 an engine of great simplicity of operation, a minimum number of parts and of high effectiveness.

To this end the invention consists in the arrangement of parts and detailed construction 20 of the mechanism set forth in the following description, shown in the accompanying drawings, and more definitely detailed in the claims hereto appended.

In the accompanying drawings, showing 25 an embodiment of my invention, more particularly designed for motor boats, Figure 1 is a side view of the engine, Fig. 2 is a horizontal section on line $x-x$ of Fig. 1, the rotor being partly broken away, Fig. 3 is a vertical section on line $y-y$ Fig. 4, and Fig. 4 is a top view, partly sectional on line $z-z$, Fig. 3.

Like characters in all the views refer to like parts.

In the drawings, 2 designates a circular 30 rotor-inclosing casing having side plates 2' 2''. At their centers the side plates are provided with the outwardly projecting hubs 2''' forming bearings for a rotor shaft 5. On diametrically opposite points on the circumference, I have shown the casing as provided with the supporting brackets 3 by which the engine may be attached to any suitable base or standards. The casing may be kept cool by any of the means ordinarily 35 used for the cylinders of explosive engines but I have shown the walls of the casing, both on the sides and circumference as provided with water-circulating passages 4 which lead from a cool water inlet pipe 4' 40 around the circumference and along the sides of the casing in the manner shown in dotted lines in Fig. 3 to a warm water outlet pipe 4''.

Formed in connection with the casing are

the explosion chambers 8 8' as will be later 55 described.

Mounted on the shaft 5 is the rotor 6 whose general form in section is shown most clearly in Fig. 2. This is in the form of a wheel, having a hub fitting the shaft 5 and an enlarged periphery approximately fitting the casing. The interior of the casing, adjacent to the periphery of the rotor is provided with circumferential packing strips 6' having elastic contact with the outer surface of the 65 rotor adjacent to its periphery.

On its periphery, the rotor is provided with one or more pockets 7 which are inclined into the periphery of the rotor in the direction of its motion. These preferably extend across 70 the face of the rotor, as shown in Fig. 4 and the mouths of the pockets are adapted at one point in the revolution of the rotor to register with the outlet of an explosion chamber 8, which is formed upon or in one piece with 75 the casing 2. The form of this chamber is shown in Fig. 3, and its walls are provided with water channels in continuation of the water channels in the walls of the casing. There may be as many of these pockets 7 as 80 desired, situated along the periphery of the rotor. I have, however, shown two of these pockets in order that the full effect of the explosion may be transmitted to the rotor.

Set on either side of the pockets 7 and as 85 near as possible adjacent to the mouths, are transverse packing strips 9. The rotor itself does not touch the interior face of the casing at any point as this would engender too great an amount of friction, but the packing 90 strips while preventing the escape of the explosive force bear but lightly upon the interior face of the casing, thus allowing the rotor to rotate with a minimum of friction.

While the explosion chamber 8 and the 95 pockets 7 provide for rotation in one direction, I also provide the diametrically opposite explosion chamber 8' and the pockets 7' 7' oppositely inclined to the pockets 7 in order that the rotor may be driven in either 100 direction as desired. It will be understood, of course, that in the rotation of the rotor the pockets 7 will act in connection with the explosion chamber 8, while the pockets 7' will only align with the mouth of the explosion 105 chamber after the explosion has taken place and its force has been transmitted to the rotor; whereas when the rotor is moving in

the opposite direction the pockets 7' will first come into alinement with the outlet of the explosion chamber 8' and will receive the force of its explosion, which of course is 5 timed to that end.

Located preferably on the upper part of the casing midway between the two explosion chambers 8 and 8', is the exhaust outlet 10, shown best in Fig. 3 whose inlet opening 10 alines with the mouths of pockets 7, 7 or 7', 7'.

11, 11 are the inlet pipes for the gasolene or other explosive mixture. These are preferably located, as in Fig. 1, upon the side 2" of casing 2, the outer ends of said pipes entering the inlet chambers as shown, and the inner ends being connected by a three-way coupling 12, which is connected to an inlet pipe 12' leading to a charge-compressing pump by which the charge is kept at a high 20 compression before being allowed to enter the explosive chambers 8 or 8'. A hand lever 13 is connected to the usual three-way valve located inside of the coupling 12, whereby the charge may be directed into either one 25 of the explosion chambers 8 or 8'.

I have shown the charge-compressing pump 14 as formed upon or attached to the lower portion of the side plate 2", the piston of which is reciprocated through the piston rod 30 14' and the eccentric 14" mounted upon the end of the shaft 5. The eccentric and the compressor pump are of common construction familiar to all those who are acquainted with the art and need not be specifically described.

The charging pipes 11, 11 at the ends which enter the explosion chambers are provided with the puppet valves 12" which open 40 to allow the entrance of an explosive charge under pressure into the explosion chambers and which automatically close when an explosion occurs. It is to be, however, understood that any other form of valve mechanism may be used to control the inlet ends of 45 the pipes 11.

The ignition of the explosive charge in my motor is accomplished through the making of contact between the two electrodes, which are actuated to this end by a rotating cam 50 plate.

In detail the ignition device I deem it preferable to use, comprises a fixed firing pin 15 and a movable contact pin 16, having at its inner end the contact plate 16'. At its 55 outer end the movable contact pin 16 is provided with an enlarged head 16" carrying an anti-friction wheel. Between the enlarged head 16" and the face of the casing is located a spring 16' which acts to keep the contact plate 16' against the pin 15 and thus to close the circuit through the electrodes.

To actuate the ignition device, I have provided the fly wheel 17 mounted on the shaft 5, with an elevation or protuberance 60 17' on its inner face, having inclined sides, as

shown in Fig. 2, adapted to contact with the wheel on the outer end of pin 16, to force in said pin and break the contact between the electrodes. The pins 15 and 16 are each insulated from the plate 2', and are connected in circuit with each other and any suitable source of electricity. -

In order that the circuit may be permanently broken in that ignition apparatus which is located in the inactive explosion chamber, I connect the hand lever 13 by rods 13' and cross bars 13" with a pivoted lever 18 which at its free end is formed with a wedge-shaped termination adapted to engage with the projecting wedge-shaped lug 16' on the head 16. Thus when the lever 13 is thrown over to close the inlet to one explosion chamber, and open it to the other, the ignition circuit is likewise broken in the inactive chamber.

The operation of my engine is as follows: The explosive mixture is drawn from any suitable carbureter into the compressing pump 14. It is then forced into the connecting pipe 12' and one of the pipes 11 to the explosion cylinder. Supposing that the explosion cylinder is charged with a highly compressed mixture, the contact is broken between the electrodes of the ignition device at the instant that the pockets 7 or 7' 25 are in register with the outlet from the explosion chambers 8 or 8'. The explosion acts through the pockets tangentially upon the rotor to rotate the same. The force of the explosion closes the inlet valve but immediately thereafter the compression in the explosion chamber is reduced the inlet valve opens and a fresh charge is forced into the explosion chamber awaiting the instant for the next explosion which, as before explained, acts about when the pocket 7 or 7' arrives again at the outlet of the explosion chamber.

It is obvious that there may be as many pockets in the rotor as desired. I have 110 shown only one set of pockets which practically constitutes one pocket but it is obvious that I need not be limited in any way to this number, the only change required in the mechanism being that the electrodes operate 115 as many times as there are pockets in the rotor and that further the fly wheel is provided with as many protuberances 17' as there are pockets, or in other words, as there are explosions taking place during the complete rotation of the rotor.

It is obvious also that I may use means for cleansing the interior of the explosion chamber between explosions and before the inlet of a new charge, without in any way 120 altering the character of my invention.

If it is desired to reverse the rotation of the engine, it is only necessary to throw over the hand lever 13 which will reverse the three-way valve in the interior of the coup- 125

ing inclosing the same and will direct the charge to the opposite explosion chamber, at the same time breaking the circuit of one ignition device and allowing the circuit to be completed on the other ignition device.

My invention is particularly applicable to motor boats for the reason that it is a rotary engine and therefore capable of direct engagement with the propeller shaft but I do not wish to limit myself to this construction as it may be also applicable to automobile propulsion, or to stationary engines. My engine is simple, direct in its operation, has no complicated parts liable to get out of order, has a minimum of vibration and is extremely compact.

Having described my invention what I claim is:

1. In a rotary explosive engine, a rotor having two sets of tangential pockets in the periphery thereof, each side inclined in opposite directions, a casing surrounding the rotor, means for preventing the escape of gases from the pockets into the space between the rotor and casing, two explosion chambers, the outlets of each oppositely inclined in the direction of the inclination of the pockets in the rotor, means for compressing an explosive charge in one or the other of said chambers, means for igniting the charge in one or the other of said chambers, and an exhaust outlet from said casing.

2. In a rotary explosive engine, a rotor having two series of tangential pockets in the periphery thereof extending in opposite directions, the openings of said pockets extending entirely across the periphery of said rotor, means for preventing the escape of gases from the pockets into the space between the rotor and the casing, two explosion chambers having outlets commensurate with the outlets of the rotor pockets, the outlet from one chamber being oppositely inclined to the outlet of the other, and coinciding in inclination with the inclination of the pockets in the rotor, an exhaust pipe opening into the rotor casing and located between the explosion chambers, pipes entering the explosion chambers for the introduction of a charge thereto, valves in the outlets of said pipes closing against the inside pressure and opening to outside pressure, a three-way coupling connecting said pipe, a pipe leading from said three-way coupling to a charge-compressing pump, means for operating the valve in said coupling to direct the charge either to one or the other explosion chamber, and means for igniting the charge in either of said chambers.

3. In a rotary explosive engine, a rotor having two series of tangential pockets in the periphery thereof extending in opposite directions, the openings of said pockets extending entirely across the periphery of said

rotor, means for preventing the escape of gases from the pockets into the space between the rotor and the casing, two oppositely placed explosion chambers having outlets commensurate with the outlets of the rotor pockets, the outlet from one chamber being oppositely inclined to the outlet of the other and coinciding in inclination with the inclination of the pockets in the rotor, an exhaust pipe opening into the rotor casing and located between the explosion chambers, pipes entering the explosion chambers for the introduction of a charge thereto, valve in the outlets of said pipes closing against inside pressure and opening to outside pressure, a three-way coupling connecting said pipe, a pipe leading from said three-way coupling to a charge-compressing pump, a hand lever for actuating the valve in said coupling, electric igniting devices located in each explosion chamber, and means for breaking the circuit of said ignition devices, in one or the other of said explosion chambers.

4. In a rotary explosive engine, a rotor having two adjacent tangential pockets in the periphery thereof inclined in the same direction, a casing surrounding the rotor, a shaft passing through said casing on which the rotor is mounted, means for preventing the escape of gases between the rotor and the casing, an explosion chamber having an outlet inclined in the direction of the inclination of the pockets, said outlet being large enough to register with the outlets from both rotor pockets at the same time, means for preventing the escape of gases from said rotor pockets located on either side of the said pockets, means for compressing an explosive charge in said explosion chamber, means for igniting said charge, and an exhaust outlet from said casing.

5. In a rotary explosive engine, a rotor having tangential pockets in the periphery thereof, a casing inclosing said rotor, an explosion chamber having an opening therefrom registering with said pockets at one point in the revolution of the rotor, an exhaust pipe leading from said casing and adapted to register with said pockets and resilient strips attached to the rotor and located on either side of said rotor pockets and contacting with the inner face of the casing.

6. In a rotary explosive engine, a rotor having two series of tangential pockets in the periphery thereof extending in opposite directions, the openings of said pockets extending entirely across the periphery of said rotor, means for preventing the escape of gases from the pockets into the space between the rotor and the casing, two oppositely placed explosion chambers having outlets commensurate with the outlets of the rotor pockets, the outlet from one chamber being oppositely inclined to the inclination

of the other and coinciding in inclination with the inclination of the pockets in the rotor, an exhaust pipe opening into the rotor and located between the explosion chambers, 5 pipes entering the explosion chambers for the introduction of a charge thereto, valves in the outlets of said pipes closing against inside pressure and opening to outside pressure, a three-way coupling connecting said 10 pipe, a pipe leading from said three-way coupling to a charge-compressing pump, a hand lever for actuating the valve in said coupling, fixed electrodes in each explosion chamber, movable electrodes in each explosion 15 chamber in contact with the fixed electrodes, electrical connections from said electrodes, and means actuated by the rotation of the rotor acting to break the contact between said fixed electrodes and said movable 20 electrode in one of the said chambers.

7. In a rotary explosive engine, a rotor having two series of tangential pockets in the periphery thereof extending in opposite directions, the openings of said pockets extending entirely across the periphery of said 25 rotor, means for preventing the escape of gases from the pockets into the space between the rotor and the casing, two oppositely placed explosion chambers having outlets commensurate with the outlets of the rotor pockets, the outlet from one chamber being oppositely inclined to the inclination of the other and coinciding in inclination with the inclination of the pockets in the 30 rotor, an exhaust pipe opening into the rotor and located between the explosion chambers, pipes entering the explosion chambers for the introduction of a charge thereto, valves in the outlets of said pipes closing against 35 inside pressure and opening to outside pressure, a three-way coupling connecting said pipe, a pipe leading from said three-way coupling to a charge-compressing pump, a hand lever for actuating the valve in said coupling, fixed electrodes in each explosion chamber, movable electrodes in each explosion 40 chamber in contact with the fixed electrodes, and having a spindle projecting out of the side of said casing, electrical connections from said electrodes, a fly wheel mounted on the shaft of the rotor and having a protuberance thereon adapted to engage with the spindle of the movable electrode, to force said electrode inward and break the contact between the fixed and movable electrode, a pivoted arm one end of which is adapted to engage with the spindle of the movable electrode, and 45 connections between the other end of said pivoted arm and the hand lever whereby when the valve is turned to direct the charge from one to the other of the explosion chambers the said pivoted arm shall be connected to force in the movable electrode and break the circuit of the ignition device for said inactive chamber.

8. In a rotary explosive engine, a rotor having two series of tangential pockets in the periphery thereof extending in opposite directions, the openings of said pockets extending entirely across the periphery of said 60 rotor, means for preventing the escape of gases from the pockets into the space between the rotor and the casing, two oppositely placed explosion chambers having outlets commensurate with the outlets of the rotor pockets, the outlet from one chamber being oppositely inclined to the inclination of the other and coinciding in inclination with the inclination of the pockets in the 65 rotor, an exhaust pipe opening into the rotor and located between the explosion chambers, pipes entering the explosion chambers for the introduction of a charge thereto, valves in the outlets of said pipes closing against 70 inside pressure and opening to outside pressure, a three-way coupling connecting said pipe, a pipe leading from said three-way coupling to a charge-compressing pump, a hand lever for actuating the valve in said coupling, fixed electrodes in each explosion chamber, movable electrodes in each explosion 75 chamber in contact with the fixed electrodes, and having a spindle projecting out of the side of said casing, electrical connections from said electrodes, a fly wheel mounted on the shaft of the rotor and having a protuberance thereon adapted to engage with the spindle of the movable electrode, to force said electrode inward and break the contact between the fixed and movable electrode, a pivoted arm one end of which is adapted to engage with the spindle of the movable electrode, and 80 connections between the other end of said pivoted arm and the hand lever whereby when the valve is turned to direct the charge from one to the other of the explosion chambers the said pivoted arm shall be connected to force in the movable electrode and break the circuit of the ignition device for said inactive chamber.

In testimony whereof, I have signed my name to this specification in the presence of 105 two subscribing witnesses, this 12 day of March, 1907.

GUY L. FAIRBROTHER.
